DESIGN FOR A GAME APPARATUS

Herbert G. Breitenstein, Chicago, Ill., assignor to Raymond T. Moloney, Chicago, Ill.

Application June 22, 1934, Serial No. 52,281

Term of patent 3½ years

To all whom it may concern:

Be it known that I, HERBERT G. BREITENSTEIN, a citizen of the United States, residing at Chicago, in the county of Cook and State of Illinois, have invented a new, original, and ornamental Design for a Game Apparatus, of which the following is a specification, reference being had to the accompanying drawing, forming part thereof.

The drawing shows a perspective view of my design for the game apparatus.

I claim:

The ornamental design for a game apparatus, as shown.

HERBERT G. BREITENSTEIN.
